FUNNEL GUIDE BRACKET

John A. Neren, Media, Pa., assignor to American Viscose Corporation, Wilmington, Del., a corporation of Delaware

Application February 18, 1942, Serial No. 431,318

15 Claims. (Cl. 57—76)

This invention relates to a bracket for supporting a guide for directing and traversing a filamentary bundle or thread while being collected in the form of, or while being withdrawn from, a wound, twisted, cake or package.

While the bracket herein disclosed has been designed especially for association with the funnel guide and centrifugal spinning bucket in an artificial silk spinning machine for collecting recently spun and still unfinished filaments, it nevertheless is applicable for supporting similar relatively long guides which traverse longitudinally and especially in situations where it may be necessary or desirable to withdraw the guide from its scene of operation while still traversing, especially where a limited space is available for the withdrawal of the guide.

In the specification and claims, the expression "funnel guide" is intended to cover guides which are essentially equivalent in function to the funnel guide per se regardless of variations which may involve a departure from what is generally considered a true funnel shape.

In the drawings, illustrative of the invention, Figure 1 is a side elevation, partially in cross-section, of the bracket and associated parts,

Figure 2 is a plan view of the bracket with the funnel guide removed,

Figure 3 is a side elevation of the device showing the parts in an intermediate position,

Figure 4 is a side elevation of the device showing the funnel guide swung clear out of the way,

Figure 5 is a side elevation of a modified form of linkage, and Figure 6 is a plan view of the modified form of linkage shown in Figure 5.

Figures 1 to 4 show the device in position over a centrifugal box in a spinning machine. The spinning box 2, shown in dotted outline, is housed within a casing 3 which is provided with a cover 4 which may be removed for facilitating removal of the spinning box. The cover of the casing is provided with a central opening 5 through which the funnel guide 6 may traverse. Two parallel rails or rods 7 and 8, which extend the full length of the machine, and which are reciprocated vertically by suitable known mechanisms (not shown) support the bracket between two bearings 9 and 10 suitably spaced along the rods and fastened thereto, such as by being clamped or bolted to a common plate 11 beneath the two rods.

The funnel guide 6 is supported at its upper portion or neck by a member having the form of a cylindrical sleeve 12 provided at its upper end with a flange 13, the opposite sides of which are in turn provided with upstanding ears 14 and 15.

and 15. The external surfaces of the ears as well as the adjacent peripheral surface of the flange are flattened to provide a satisfactory pivotal bearing surface. This sleeve 12 telescopes within a cylindrical recess within the upper face of the cup-like member 17 which has an oval outline as viewed in Figure 2. The cup-like member is provided with a bore 18 through its bottom within which the funnel may slide. Two parallel arms 19 and 20 extend from opposite ends of the cup-like member 17 and are provided with trunnions 21 and 22 extending outwardly therefrom at their other ends. These trunnions are pivotally disposed within upstanding ears 23 and 24 on the bearings 9 and 10 upon the rails. The arms rest upon the top surface of the bearings 9 and 10 which act to limit the clockwise motion of the arms as viewed in Figure 1. Each of these arms are provided with slots 25 and 26 and with offset or stepped portions 27 and 28 which cooperate with the other parts of the device in a manner which will appear from the description hereinafter.

The funnel supporting sleeve 12 is pivotally supported by means of the ears 14 and 15 within a yoke 29 at 30 and 31. As shown, the other end of this yoke is branched and is provided with a pair of trunnions 32 and 33 which extend into and cooperate with the slots 25 and 26 respectively of the two bracket arms. This yoke 29 is provided with pivotal connections at 34 and 35 with a pair of links 36 and 37 whose other ends are pivoted to upstanding ears 38 and 39 upon the cup-like member 17. The distance from the pivotal axis intermediate of the yoke through 34 and 35 to the axis of the trunnions 32 and 33 thereof is substantially one-half the distance from the pivotal axis of the funnel supporting sleeve 12 to the axis of the trunnions 32 and 33. A guide member 40 is suitably supported between the two bearings 9 and 10, such as by mounting upon the lower plate 11. This guide 40 is of hook-like conformation, the body 41 of the hook portion being in the shape of a quadrant. The quadrant portion overhangs the base portion 42 of the hook-like guide, and, as shown, a re-entrant slot 43 (see Fig. 4) separates the two portions. This guide member also has a portion 44 projecting upwardly at the upper end of the quadrant portion 41. The yoke 29, at its end removed from the funnel supporting end, is provided with a pin 45 which extends transversely between the forked elements of the yoke and is substantially coaxial with trunnions 32 and 33. This pin is adapted to follow about

the contour of the quadrant as will be herein-after described.

In operation of the device, withdrawal of the funnel from the spinning box and its surrounding casing may be accomplished regardless of continuation of the reciprocating motion and regardless of the position of the funnel bracket with respect to its traverse merely by taking hold of the funnel or the flange 13 about the funnel supporting sleeve and lifting it upwards. In 10 doing so, the intermediate position of Figure 3 is attained. Thereafter, the whole funnel bracket may be swung about the trunnions 21 and 22 of the arms into the position of Figure 4 where it rests by gravity, further motion of the pin 15 45 in the yoke being prevented by the upwardly projecting portion 44 of the guide member 43.

Figures 5 and 6 show one side of the linkage of a modified form of bracket (primed reference characters being applied to the parts of the modified form which correspond to the parts carrying unprimed characters in Figures 1 to 4) in which all of the relations hereinbefore described with respect to Figures 1 to 4 are maintained with the single exception that the axis of the pin 45' and the trunnions (32' being shown) on the yoke is offset from the pivotal axis of the trunnions (21' being shown) of the arms (13' being shown) of the bracket. This assures that no pivotal action of the bracket arms 19' and 29' can occur until after the funnel has been lifted into an intermediate position corresponding to that of Figure 3. In this embodiment the distance between the axis of the pin 45' and the pivotal axis of the funnel supporting sleeve 13' in the yoke is twice the 30 distance from the pivotal axis 34' where the links 36' and 37' are connected to the yoke to the axis of the pin.

The invention provides a mechanism for lifting a funnel and swinging it from spinning position in which the first part of the motion is a straight line motion so that no damage can befall the funnel as it is withdrawn from the casing surrounding a spinning bucket. In the second part of the motion, the funnel is swung while firmly held in fixed relationship to the several parts of the bracket into its idle position where it remains ready to be reinserted by a single movement of the hand of the operator.

While preferred embodiments of the invention have been disclosed, it is to be understood that changes and variations may be made without departing from the spirit and the scope of the invention as defined by the appended claims.

What I claim is:

1. In combination, means for supporting a funnel guide comprising two separable elements and means connecting said two elements for constraining their motion of separation to a straight line.

2. In combination, means for supporting a funnel guide comprising two separable elements surrounding said guide, and means connecting said two elements for constraining their motion of separation to a substantially straight line longitudinally of said guide.

3. In combination, reciprocal means for supporting a funnel guide comprising two separable elements surrounding said guide, and means connecting said two elements for constraining their motion of separation to a substantially straight line longitudinally of said guide.

4. In combination, means for supporting a funnel guide comprising a pivotally supported bracket, a guide-gripping member carried by said

bracket and a straight-line motion mechanism comprising a plurality of links connecting said member to said bracket.

5. In combination, a support, a bracket pivotally mounted on said support, a member adapted to support a funnel guide carried by said bracket, a straight-line motion mechanism connecting said member to said bracket, and an element associated with said support having guiding means cooperating with said straight-line motion mechanism to prevent pivotal motion of said bracket during a predetermined substantially straight-line displacement of said member from said bracket.

6. In combination, a reciprocable support, a bracket pivotally mounted on said support, a member adapted to support a funnel guide carried by said bracket, a straight-line motion mechanism connecting said member to said bracket, and an element associated with said support having guiding means cooperating with said straight-line motion mechanism to prevent pivotal motion of said bracket during a predetermined substantially straight-line displacement of said member from said bracket.

7. In combination, a support, a bracket pivotally mounted on said support, a member adapted to support a funnel guide carried by said bracket, a straight-line motion mechanism connecting said member to said bracket, said bracket having means for maintaining the axis of the funnel guide in substantially fixed relationship to said bracket during the substantially straight-line motion of said member and funnel guide, and an element associated with said support having guiding means cooperating with said straight-line motion mechanism to prevent pivotal motion of said bracket during a predetermined substantially straight-line displacement of said member from said bracket.

8. In combination, a support, a slotted bracket pivotally mounted on said support, a member adapted to support a funnel guide carried by said bracket, a straight-line motion mechanism connecting said member to said bracket, the connection of the straight-line motion mechanism to said bracket comprising pin means arranged to project into a slot in said bracket, a guide member on said support, pin means on said straight-line motion mechanism co-axial with the first pin means arranged to cooperate with said guide member to prevent pivotal motion of said bracket during a predetermined substantially straight-line displacement of said member from said bracket.

9. In combination, a support, a slotted bracket pivotally mounted on said support, a member adapted to support a funnel guide carried by said bracket, a straight-line motion mechanism connecting said member to said bracket, the connection of the straight-line motion mechanism to said bracket comprising pin means arranged to project into a slot in said bracket, a guide member on said support, pin means on said straight-line motion mechanism co-axial with the first pin means arranged to cooperate with said guide member, the axis of said co-axial pin means being offset with respect to the pivotal axis of said bracket.

10. In combination, a support, a slotted bracket pivotally mounted in said support, a member adapted to support a funnel guide carried by said bracket, a straight-line motion mechanism connecting said member to said bracket, the connection of the straight-line motion

mechanism to said bracket comprising a combination of links, one of which is pivotally connected to said member and has pin means arranged to project into a slot in said bracket, and another of which, half the length of the first link, is pivoted at one end to the bracket adjacent the funnel guide and at the other end to the first link at substantially its midpoint, a guide member on said support, additional pin means on the first link co-axial with the first pin means arranged to cooperate with said guide member to prevent pivotal motion of said bracket during a predetermined substantially straight-line displacement of said member from said bracket.

11. In combination, a support, a slotted bracket pivotally mounted on said support, a member adapted to support a funnel guide carried by said bracket, a straight-line motion mechanism connecting said member to said bracket, said bracket having means for maintaining the axis of the funnel guide in substantially fixed relationship to said bracket during the substantially straight-line motion of said member and funnel guide, the connection of the straight-line motion mechanism to said bracket comprising a combination of links, one of which is pivotally connected to said member and has pin means arranged to project into a slot in said bracket, and another of which, half the length of the first link, is pivoted at one end to the bracket adjacent the funnel guide and at the other end to the first link at substantially its midpoint, a guide member on said support, additional pin means on the first link co-axial with the first pin means arranged to cooperate with said guide member to prevent pivotal motion of said bracket during a predetermined substantially straight-line displacement of said member from said bracket.

12. In combination, a support, a slotted bracket pivotally mounted on said support, a member adapted to support a funnel guide carried by said bracket, a straight-line motion mechanism connecting said member to said bracket, said bracket having means for maintaining the axis of the funnel guide in substantially fixed relationship to said bracket during the straight-line motion of said member and funnel

guide, the connection of the straight-line motion mechanism to said bracket comprising a combination of links, one of which is pivotally connected to said member and has pin means arranged to project into a slot in said bracket, and another of which, half the length of the first link, is pivoted at one end to the bracket adjacent the funnel guide and at the other end to the first link at substantially its midpoint, a guide member on said support, additional pin means on the first link co-axial with the first pin means arranged to cooperate with said guide member, the axis of said co-axial pin means being offset with respect to the pivotal axis of said bracket.

13. In combination, means for normally supporting a funnel guide in an operative position and means comprising a plurality of links associated therewith for constraining displacement of said guide with respect to a part of said supporting means to a substantially straight-line in a direction substantially longitudinally of the funnel for a distance equal to the greater part of the depth to which the funnel may normally extend within a spinning bucket.

14. A device for normally supporting a funnel guide in operative position, means associated therewith comprising a plurality of links for constraining displacement of said guide with respect to a part of said device to a substantially straight-line in a direction longitudinally of the funnel for a distance equal to the greater part of the depth to which the funnel may normally extend within a spinning bucket into an intermediate position, said device being pivotally mounted for permitting swinging of said device bodily, and means preventing said swinging motion in the normal position of said device until said intermediate position is attained.

15. In combination, means for supporting a funnel guide comprising two separable elements and means connecting said two elements for constraining their motion of separation to a straight-line longitudinally of the funnel for a distance equal to the greater part of the depth to which the funnel may normally extend within a spinning bucket.

JOHN A. NEREN.
